CLAIM

The ornamental design for a portable power bank, as shown and described.

DESCRIPTION

FIG. 1 is a front perspective view of a portable power bank showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a rear perspective view thereof; and,

FIG. 9 is a rear perspective view thereof showing that power plug prongs are folded.

The broken lines are shown for illustrative purposes only and form no part of the claimed design.
